UNITED STATES PATENT OFFICE.

RICHARD LA FRANCE, OF TOLEDO, OHIO, ASSIGNOR TO THE OWENS BOTTLE MACHINE COMPANY, OF TOLEDO, OHIO, A CORPORATION OF OHIO.

GLASS-FORMING MACHINE.

1,319,098.

Specification of Letters Patent. Patented Oct. 21, 1919.

Application filed March 12, 1917. Serial No. 154,192.

To all whom it may concern:

Be it known that I, RICHARD LA FRANCE, a citizen of the United States, residing at Toledo, in the county of Lucas and State 5 of Ohio, have invented new and useful Improvements in Glass-Forming Machines, of which the following is a specification.

My invention relates to glass forming machines, and particularly to means for temporarily supporting the glass article when the 10 finishing molds are opened.

The invention is as herein shown, particularly adapted for use on the well known Owens type of bottle-blowing machines. 15 These machines comprise a rotary frame on which are mounted a number of bottle forming units, each including a blank mold in which the glass is gathered to form a blank, and a finishing mold in which the blank is 20 blown to its final form. After the blowing operation is completed, the sectional blow mold is opened and the bottle ejected.

It is customary to provide on these machines a device to engage the top of the 25 bottle and temporarily hold it as the blow-mold opens, to thereby prevent the bottle as it falls from rubbing against and wearing the edge of the mold and also to prevent it from being misplaced by sticking to the 30 mold. Such a device is shown, for example, in the patent to Bock, 1,063,108.

It has been found in practice that the usual head which presses against the top of the bottle wears rapidly and unevenly and 35 must be frequently replaced by a new head. This necessitates the stopping of the machine and loss of time, thereby reducing the output of the machine, and also involves considerable expense for the new heads.

An object of the present invention is to 40 overcome this objection by the provision of a head comprising a bottle engaging disk, which is inexpensive and may be quickly removed and replaced by a new disk while 45 the machine is running, thereby effecting economy of operation and increasing the output of the machine.

In its preferred form, the invention comprises a rock shaft mounted in a support 50 on the blow-mold carrying frame. As said frame approaches the position at which the blow-mold is opened, a cam on the machine frame moves the shaft endwise while a second cam rocks the shaft. A head carried 55 by an arm on the rock shaft is thereby swung

to position over the bottle and moved downward to bring a bottle-engaging disk thereon against the neck of the bottle. The bottle is thus momentarily held by the disk while the mold opens and the head is then 60 withdrawn to permit the bottle to fall from the machine.

The disk is preferably made of wood and is slidably mounted in its support and held by a spring clip so that it may be readily 65 removed and a new one substituted while the machine is running. The disks are inexpensive, and the material well adapted for the purpose in hand, as the surface of the wood becomes slightly charred by the hot glass 70 and provides a heat insulating surface which does not crack the bottle necks.

Other features and advantages will appear hereinafter.

In the accompanying drawings Figure 1 75 is a part sectional elevation of a construction embodying the principles of my invention. Fig. 2 is an elevation showing a portion of the rock shaft and operating cams therefor. Fig. 3 is a section at the line 3—3' 80 on Fig. 2. Fig. 4 is a bottom plan of the disk carrying arm and head. Fig. 5 is an elevation of the head and removable disk. Figs. 6, 7 and 8 are diagrammatic views 85 illustrating the relative positions of parts in successive steps in the operation.

Referring to Fig. 1, the blow-mold 9 comprises sections hinged on a pivot pin 10, mounted on an arm or bracket 11, secured to the mold carrying frame 12. As is usual on the Owens bottle machine, the frame 12 may be one of a series of frames mounted for rotation about a vertical axis and each carrying a blow mold and operating mechanism therefor. The frame 12 carries a cam roller 95 13 running on a stationary cam 14 formed to lift the frame 12 during a portion of its rotation into position to permit the blow-mold to be closed around the blank formed in a blank-mold (not shown), the blank being blown to give the bottle 15 or other article its final shape in the blow-mold.

When the blow-mold 9 is opened by swinging the sections thereof apart, the bottle falls from the mold. In order to prevent wear of 105 the molds by the bottles striking and rubbing over the edges thereof as the mold is opened, and also to prevent the bottle from sticking to the mold, there is provided a device to temporarily engage the upper end 110

of the bottle and hold it until the molds are opened sufficiently to permit the bottle when released from said holding means, to clear the mold. As the head or device which thus engages the neck of the bottle is subject to comparatively rapid wear and must be frequently renewed, the present invention provides a disk which is readily removable while the machine is in operation and which can be quickly replaced when worn by a new disk without loss of time or interrupting the continuous operation of the machine.

As herein shown, this disk 16 is detachably mounted in a head 17 having a stem 18 mounted in an arm 19. Said stem 18 may extend through an opening in the arm and is secured by a pin 20. The arm 19 may also be provided with a sleeve 21 in which the stem 18 is guided and a spring 22 surrounding said sleeve between the arm 19 and the head 17, provide suitable pressure of the disk for holding the bottle, but permits the disk 16 to yield upwardly preventing excessive pressure on the bottle.

The head 17 is provided with a depending flange 23 extending about half way around its periphery and having an inner inclined or beveled holding surface to engage the beveled surface 24 of the disk, thereby providing a dove-tailed sliding connection between the said head and the disk, being interlocked when the latter is in position. When the disk has been slid into position in the head 17, it is securely held in such position by a spring clip or latch 25. Said clip is formed by a coiled spring mounted on a pin 26 held in lugs 27 on the head 17, the clip comprising a downwardly extending bail to engage the edge of the disk 16 and hold it firmly in position. The disk may be readily removed by first lifting the spring clip or by moving the disk outward against the tension of said clip and forcing the latter upwardly. The disk is preferably made of wood and the under surface thereof is concave as shown at 28 to fit and securely hold the neck of the bottle. It will be seen that with this construction a disk when worn may be readily removed and replaced while the machine is in operation. It is found in practice that the wooden disks are particularly adapted for the present purpose, not only because they are inexpensive but the heat of the bottles is such as to assist in forming the surface of the disk to the contour of the bottle end and to slightly char the wood, providing a heat insulating surface which does not chill or crack the bottles.

The rock arm 19 is mounted on a rock shaft 30 arranged for rotative and end-wise movement in the bracket 11. The latter is formed with an integral sleeve or cylindrical extension 31 in which is slidably mounted a cylinder 32 held against rotative movement by

the guide pins 33, Fig. 3. The lower portion of the rock shaft 30 consists of an enlarged cylindrical portion 30' which is rotative in the cylinder 32, but held against relative end-wise movement therein by means of a pin or cam roller 34 secured to the rock shaft and movable transversely in a transverse slot 35 formed in the sleeve 32. The roller 34 also extends through a cam slot in the extension 31, which slot comprises a vertical section 36 and an inclined section 37.

The movements of the rock shaft 30 are controlled as hereinafter explained by a cam 38 formed on a bracket 39 secured to the stationary frame 40 of the machine. The shaft 30 comprises telescopic sections 42 and 43 permitting its length to be adjusted, said sections being locked in adjusted position by a pin 41. The upper section 42 is cut away on opposite sides to produce flat surfaces, the section 43 having a correspondingly shaped bore, so that relative rotation of said sections is prevented. A coil spring 44 is mounted on the section 43 between a collar 45 thereon and a cap 46 on the upper end of the sleeve 31, and holds the roller 41 up against the cam 38.

The arm 19 is provided with a bifurcated head 47 to receive the shaft section 42, and is adjustable lengthwise of the shaft by means of an adjusting ring or nut 48 threaded on the shaft, said nut being received in a slot in the head 47. Clamping bolts 49 secure the arm in adjusted position. The sleeve 31 may be provided with a protecting hood 50 extending downward over the cam slot and roller in said sleeve.

In operation, the mold carrying frame 12 rotates continuously and the blow-mold 9 thereon during each complete rotation receives a blank which is blown therein and the bottle thus formed discharged before the mold completes its rotation. As the mold approaches discharging position the roller 41 strikes the cam 38 and the rock shaft is thereby pulled downward. During the initial portion of this downward movement, the roller 34 travels in the inclined section 37 of the cam slot, thereby swinging the head 17 inwardly from its normal position (Fig. 6) at one side of the mold, to a position (Fig. 7) directly over the mold. During the continued downward movement of the rock shaft, the roller 34 moves in the vertical portion 36 of the slot, so that the head 17 is moved downward to engage the top of the bottle (Fig. 8). The mold is now opened while the bottle is held by the head 17. When the roller 41 reaches the opposite incline of the cam 38, the head 17 is lifted to release the bottle, the mold by this time having been opened wide enough to permit the bottle to drop out without striking the edges of the mold.

Variations may be resorted to within the scope of my invention.

What I claim is:

1. In a glass forming machine, the combination of a mold comprising sections separable to open the mold for discharging an article formed therein, a head, a wooden disk carried by said head to engage said article and hold it during the opening of the mold, and means to releasably hold the disk in position on the head and permitting the quick removal of the disk from the head.
2. The combination with a mold having laterally separable sections, of a device for temporarily holding an article while the mold is being opened, said device comprising a head movable toward and from the article, a heat insulating contact member having a dovetailed sliding connection with said head, and a spring latch releasably holding the contact member in position on said head and permitting its instantaneous removal from the head.
3. The combination with a mold having laterally separable sections, of a device for temporarily holding an article while the mold is being opened, said device comprising a head movable toward and from the article, a contact member formed of wood and carried by said head for engaging said article, and a spring clip for detachably holding the contact member on said head.
4. In a bottle making machine, the combination of a head, a disk, a supporting flange on said head shaped to form a groove to receive the periphery of the disk, the disk being removable from the head only by a sliding movement transverse to its axis, a latch coöoperating with said flange to hold the disk in position on the head and permitting the quick removal of the disk, and automatic means to remove said head into and out of position to cause the disk to hold a bottle formed on the machine.
5. In a bottle making machine, the combination of a head, a disk, a supporting flange on said head to engage the periphery of the disk, a latch coöoperating with said flange to hold the disk in position on said head, and means to move the head into and out of position to cause said surface to engage the neck end of the bottle.
6. The combination with a mold having laterally separable sections, of a device for temporarily holding an article while the mold is being opened, said device comprising a head movable toward and from the article, a contact element having an interlocking sliding connection with said head, a spring clip to releasably hold said element in position on the head, and timed mechanism automatically operable to move the holding device into and out of position to engage said contact element with said article.
7. In a glass forming machine, the combination of a mold in which a charge of glass is formed, a device to hold the glass while the mold is being opened, said device comprising a support and a contact piece on the support, means to actuate said device and thereby move the contact piece into and out of position to engage and hold the glass, said contact piece consisting of heat insulating material mounted for instantaneous removal from its support.
8. In a glass forming machine, the combination of a mold in which a charge of glass is formed, a device to hold the glass while the mold is being opened, said device comprising a support and a contact piece, said support having a guideway along which the contact piece is slidable into and out of operative position on the support, a latch to hold the contact piece in said operative position, and automatic means to periodically actuate said device and thereby move the contact piece into and out of position to engage and hold the glass.

Signed at Toledo, in the county of Lucas and State of Ohio, this 7th day of March, 1917.

RICHARD LA FRANCE.
